CLAIM

We claim the ornamental design for a cast cover, as shown and described.

DESCRIPTION

FIG. 1 is a right side elevational view of a cast cover showing our new design;

FIG. 2 is a front elevational view thereof;

FIG. 3 is a rear elevational view thereof;

FIG. 4 is a left side elevational view thereof;

FIG. 5 is a top plan view thereof;

FIG. 6 is a bottom plan view thereof; and,

FIG. 7 is a front perspective view thereof, the broken line showing of the human form is for illustrative purposes only and forms no part of the claimed design.
